ROBERT BURGES SNOW, OF NEW YORK, N. Y.

WASHING AND CONVEYING MECHANISM FOR MACHINES FOR WASHING AND DRYING SENSITIZED PAPER.

1,116,943.

Specification of Letters Patent. Patented Nov. 10, 1914.

Application filed September 17, 1913. Serial No. 790,245.

To all whom it may concern:

Be it known that I, ROBERT B. SNOW, a citizen of the United States, and a resident of the city of New York, borough of Manhattan, in the county and State of New York, have invented a new and Improved Washing and Conveying Mechanism for Machines for Washing and Drying Sensitized Paper, of which the following is a full, clear, and exact description.

My invention has special reference to an improved washing and conveying mechanism for machines employed for washing and drying sensitized paper, and more particularly to a machine which is adapted for effectively washing and drying sensitized paper or prints in long or short lengths and for discharging them on to a platform or table after they are dried.

A further object of the invention is comprehended in the provision of a machine of the character described which embodies a supporting frame in which is mounted a pan designed to contain a washing fluid, such as water, while a foraminous or screen drum is rotatably mounted in a partly submerged position in said fluid and designed by means of a plurality of carrying belts arranged in a novel manner, to receive the sensitized paper from a suitable source, or fed in any desired manner as from a printing machine, to cause said paper to pass under the drum while supported by certain of the belts for washing the paper, while a heating cylinder is also rotatably mounted in the frame and by means of a further arrangement of belts and an endless apron is caused to effectively receive the paper after having been washed and to dry and deliver the same at the opposite end of the machine.

A still further object of the invention is comprehended in the provision of a novel form of spraying apparatus or arrangement of pipes contained in the foraminous or screen drum so as to thoroughly wash the paper and renew the washing fluid continuously, as well as to assist a take-off device to cause the paper to be delivered between the apron and belts which pass around the drying cylinder, the paper being subsequently deposited upon a foldable table carried at the discharge end of the frame, while means are further provided for taking up the slack in the apron so as to effectively cause the proper feeding of the paper against crimping or folding, in addition to

means for causing the thorough absorption of the washing fluid and consequently effect the proper drying of the paper.

With the above and other objects in view, the invention resides more particularly in the peculiar combination and arrangement of parts which will be illustrated as a preferred embodiment in the accompanying drawings and described in the specification.

Reference is to be had to the accompanying drawings forming a part of this specification, in which similar characters of reference indicate corresponding parts in all the views, and in which—

Figure 1 is a plan view of the improved machine for washing and drying sensitized paper, with certain of the parts broken away and shown in section, while other of the parts, and particularly the carrying belts, are indicated in dotted lines to show the arrangement thereof in plan; Fig. 2 is a longitudinal sectional view taken on the line 2—2 in Fig. 1; Fig. 3 is an elevation of the power roller of the device, illustrating the manner of grooving the rollers for the reception of the carrying belts; Fig. 4 is an enlarged perspective view of the heating or drying cylinder, with a portion thereon broken away to show the diametrically opposite openings in the opposed ends of the cylinder; and Fig. 5 is a detail perspective view of an adjustable bearing for an idler roller designed to take up the slack in the drying apron.

In the illustrated embodiment of the invention, the device comprises a supporting frame 10 which may be of any approved type but which preferably consists of a series of vertical supports 11 braced at the top and bottom and at intermediate points by horizontal struts 12 so as to be light and strong and permit convenient access to the working parts of the machine, to be herein-after more fully described. The frame structure may be divided into two sections, being the section 13 and the section 14, in the section 13 of which, and upon suitable longitudinal braces 15, a foraminous or screen drum 16 is rotatably journaled and partly submerged in the washing fluid contained in a pan 17. This pan is also supported by the frame, the section 13 of which is shown as being at a lower elevation than the section 14, and as the pan 17 is preferably of semi-cylindrical form or semi-circular in cross section and has the drum ro-

tatably journaled therein below its axial center, the drum will be partly submerged, so that the washing fluid will cover approximately one half of its circumference. The 5 washing drum 16, which is of a cylindrical form, is preferably constructed of solid end plates 18 connected by a lateral section 19 of screen or wire mesh, and it will be found that this produces a very rigid structure, 10 sufficient to maintain the drum truly cylindrical so that the paper will feed evenly around the same without being torn or disfigured.

In order to supply the washing fluid or 15 water continuously to the pan and drum, the drum at its end portions is rotatably journaled upon a transverse supply pipe 20 suitably supported by the longitudinal braces 15, said supply pipe having near each end 20 pairs of oppositely extending radial branches 21 connected by curved sections 22 preferably covering an arc of substantially 180°, while a series of longitudinal pipes 23 connect the extremities of the radial branches 25 21 and the curved portions 22 at points equi-distantly spaced therearound. These pipes are located in close relative position to the lateral section of the drum and are disposed below the axis of the drum, as shown 30 in Fig. 2 of the drawings, while each pipe is provided with a plurality of openings through which the washing fluid or water is forced under pressure in the form of sprays so as to thoroughly wash the paper 35 interiorly. As the paper passes around the drum and is submerged within the fluid contained in the pan 17, it is obvious that the exterior face of the paper will also be thoroughly washed, and as the washing fluid or water is continuously supplied through 40 the pipe 20, the outlet is made through a pipe 25 so as to continuously renew the fluid for the proper washing of the paper by removing the foreign matter and chemicals 45 deposited in the pan.

In order to feed the paper to the drum and pan forming the washing mechanism of the machine, a roller 26 is rotatably journaled in the frame immediately above the receiving 50 end of the pan and transversely of the frame while slightly above the roller 26 and outwardly of the receiving end of the frame a roller 27 is journaled, and directly above the roller 27 a roller 28 is journaled in 55 spaced relation to the roller 27, while a smaller roller 29 is similarly journaled in the frame with its axis in horizontal alignment to the axis of the roller 26, but such roller is located a spaced distance inwardly 60 of the roller 26. Mounted at a spaced distance above the opposite end of the pan is a roller 30 and horizontally aligned therewith but journaled in the section 14 of the frame 65 10, in contra-distinction to the fact that the aforesaid rollers are journaled in the section

13, is a power roller 31, such roller being spaced from the roller 30 and having journaled directly therebeneath and adjacent the bottom of the frame a roller 32, while directly below the axis of the pan and drum 70 and spaced from the pan, a roller 33 is journaled. All of these rollers are provided with a series of peripheral grooves 34 located in spaced parallel relation, they being of uniform width throughout so that the aligned 75 grooves receive a plurality of spaced and endless belts or tapes 35 which are engaged around the rollers and which are held from longitudinal displacement or shifting against the shoulders 36 produced by the 80 grooves. These belts are engaged over the roller 26 and pass in an inclined position, as shown at 37, over the roller 27 and from the roller in the opposite direction pass beneath and around the drum 16 and into the 85 pan 17. The belts are held in snug engagement with the drum and from their submerged position pass over the rollers 30 and 31 so that the portions 38 of the belts are horizontally disposed to prevent creasing or 90 folding of the paper at this point. The belts after passing over the roller 31 extend downwardly around the rollers 32 and 33 and then upwardly in an inclined position around the roller 27 in the aforesaid manner. 95

A series of endless belts 39 are engaged around the rollers 28 and 29 and by reason of the fact that the roller 29 is located below the plane of location of the roller 26 horizontally and at a greater distance from the 100 roller 28 than the roller 26, the lower laps of the endless belts 39 will contact with the roller 26. Thus, as rotation is imparted to said rollers and belts by driving the power roller 31, as by means of a pulley 40 and a 105 belt 41, in a clockwise direction in the position shown in Fig. 2 of the drawings, the parts will be moved in the directions indicated by the arrows.

In order to drive the endless belts 39 a 110 cross belt 42 is engaged around the rollers 27 and 28, respectively, thus causing said rollers to rotate in opposite directions toward each other whereby, as the sensitized paper is fed between the rollers and between 115 the belts at the point where they converge to contact with the roller 26, the paper will freely pass between said rollers and belt and be gripped between the latter in passing over said roller and beneath the roller 120 29, which will operate to deflect the paper downward against the lower belts so as to pass between the latter and the washing drum. The paper will then be carried through the washing fluid or water between 125 said belts and drum and will be thoroughly sprayed and washed until it emerges at the opposite side of the drum. At this point a take-off device is provided which is assisted by the spraying action, tending to 130

force the paper thus washed away, from the drum, and such take-off device embodies a brush 43 which is held stationary adjacent to the periphery of the drum slightly above the axis of the latter and preferably fixed to the opposed ends of the pan or vat 17, thus serving to prevent the paper from adhering to the drum and passing around with the latter as the drum revolves. In the further travel of the paper through the machine means are provided for drying the same, and in the present instance a drying cylinder 44 in the form of a metallic shell is rotatably journaled in the section 14 in a plane 15 above the washing drum and which also serves the function of a conveying member to deliver the paper in a smooth condition. For this purpose the section 14 of the supporting frame 10 is provided with opposed 20 longitudinal braces 45 as an illustrative manner of supporting the cylinder upon a gas supply pipe 46 carried thereby, such supply pipe receiving its supply in any suitable manner at one end, as from a branch pipe 47 fitted thereto by a cap 48, while said pipe 46 is in turn provided with a plurality of burners 49 extending upwardly so as to uniformly heat the cylinder as the latter rotates when the gas exuding from the 25 burners is ignited. In order to furnish the proper draft to insure proper combustion within the cylinder, the heads or ends of the cylinder are provided with openings 50 preferably of segmental form as shown more particularly in Fig. 4 of the drawings, and located one in each end 51 diagonally opposite or at diametrically opposite sides of the axis of the cylinder, thus creating a tortuous path for the draft through the cylinder. 30

In order to convey the sensitized paper thus washed and removed from the drum by the take-off device and to pass the same under and partly around the cylinder to be dried, an endless drying apron 52 after passing over the rollers 30 and 31 to overlie the portions 38 of the belts 35 which are horizontally disposed in a rectilinear direction for some distance, so as to assist in smoothing the paper in passing over the said rollers, passes under the cylinder 44 in contact therewith. This apron is preferably of some absorbent material or cloth, such as cotton duck or canvas and after being passed over the rollers 30 and 31, extends beneath and in contact with the cylinder 44 and from thence passes upwardly and in contact with an idler or tightening roller 56, subsequently passing upwardly and over a roller 55 journaled at the discharge end of the frame and preferably in a plane higher than the roller 54, over which the apron afterward passes. The apron then passes downwardly beneath and in contact with a small roller 53 located on a plane below the

rollers 30 and 31 and in close proximity to the take-off brush 43, so that the belts 35 and the apron 52 will converge toward their points of contact with the roller 30 and assist in causing the paper to evenly pass on to said roller last mentioned. The roller 54 is journaled at the adjacent end of the section 14 of the frame above the section 13 and is located slightly rearwardly of the small roller 53, so as to contact the apron on an incline. 70

The idler or tightening roller 56 is journaled in the frame to contact with the apron 52 at the inner side of the latter and at the part thereof between the cylinder and roller 55, and in order to shift the roller 56 toward and away from the apron at this point its shaft 57 is rotatably mounted at its ends in bearing blocks 58 longitudinally adjustable in slotted bearings 59 fixed as by means of extensions 60 to the vertical struts 11 of the section 14 of the frame 10 at the discharge end of the machine. These bearings are located within the area of the frame and extend toward the receiving end thereof, 80 while swiveled to the slidable bearing blocks 58 and threaded through the end portions 61 of the bearings 59 are adjusting screws 62 having suitable hand wheels 62' by which they may be manipulated or rotated. Thus, 85 by adjusting the bearing blocks 58 longitudinally the roller 56 may be moved toward and away from the apron 52 and by causing the apron to extend out of a line described by the shortest path between the 90 points of contact of the apron with the cylinder and roller 55, the apron may be tightened by taking up the slack, and also caused to be partly deflected downwardly as indicated at 63 so as to more positively insure 95 of the discharge or release of the paper at this point. 100

The cylinder and apron coöperate to cause the feeding of the paper in the manner last mentioned, but such operation is 110 positively effected by means of a plurality of endless belts 64 which are passed around the roller 31 so as to engage alternate grooves 34 in the latter between the belts 35 and in spaced relation thereto, such belts 64 115 then traveling beneath the cylinder outwardly of the apron and assisting in holding the apron in close contact with the cylinder for thorough drying thereof and the paper which passes between the belts and 120 the apron, it being here explained that the degree in which the paper is washed and dried is controlled by or relatively proportioned to the sizes of the drum and cylinder and also to the length of time that the paper 125 is subjected to the wash and the intensity of the heat within the cylinder. The belts 64 after passing beneath the cylinder 44 are then passed over and around a roller 65 journaled transversely of the frame at the 130

discharge end of the machine in a plane slightly above the axis of the cylinder and beneath and rearwardly of the roller 56, the belts then passing downwardly around a 5 roller 66 journaled at the bottom portion of the section 14 of the frame substantially below the axis of the cylinder, and then angularly upward and around the roller 31 as heretofore explained. Owing to the fact 10 that the apron and belts 64 are spaced apart at their points of contact with the rollers 56 and 65, the paper after being dried is freed from the apron at this point and passes over the roller 65 and is discharged. 15 In order to collect the paper thus delivered by the machine, in short or long lengths, and to obviate the objections in handling the same in the cumbersome manner as now done, a foldable platform or 20 table 67 is hinged as shown at 68 to the frame slightly below the highest point of the periphery of the roller 65 and in close proximity to the latter. This table or platform may be swung downwardly against the 25 discharge end of the frame or may be held in a horizontal position as by means of supporting braces 69 pivoted at their outer ends to the table and having their upper and inner ends provided with headed studs 30 70 engageable with slotted brackets 71 fixed to the vertical struts 11 at the discharge end of the machine, such braces when disengaged from the brackets permitting the table to be lowered to occupy a minimum 35 space when not in use.

Having thus described my invention, what I claim as new and desire to secure by Letters Patent is:—

1. In a machine for washing sensitized 40 paper, the combination with a supporting frame and a fluid containing pan supported thereby; of means for causing the paper to pass through the fluid in the pan and means for removing and deflecting the paper from

45 said moving means at the discharge side of the pan, said removing and deflecting means including outwardly-acting sprays.

2. In a machine for treating sensitized 50 paper, the combination with a supporting frame and a fluid containing pan supported thereby; of means for causing, long or short lengths of paper to pass through the fluid in the pan, means for removing and deflecting the paper from said moving means 55 at the discharge side of the pan, a conveying cylinder to deliver the same in a smooth condition also supported by the frame and means for receiving the paper from said removing and deflecting means and passing 60 the same around the cylinder.

3. The combination with a supporting 65 frame and a pan supported therein; of a foraminous drum rotatably journaled within the area of the pan, a liquid spraying apparatus mounted in a fixed position within the

drum, feeding devices for causing the passage of short or long lengths of material to be washed through the fluid contained in the pan by passing the same around the drum and means to receive the paper from the drum to deliver the same in a flat condition.

4. The combination with a supporting frame and a pan supported therein; of a foraminous drum rotatably journaled within the area of the pan, a liquid spraying apparatus mounted in a fixed position within the drum, feeding devices for causing the passage of short or long lengths of material to be washed through the fluid contained in the 75 pan by passing the same around the drum, a take-off device for removing the material from the drum and causing the same to continue with said feeding devices, said spraying apparatus also serving to deflect the 80 material from the drum and means for discharging the paper.

5. The combination with a supporting frame and a pan supported therein; of a foraminous drum rotatably journaled within the area of the pan, a liquid spraying apparatus mounted in a fixed position within the drum, feeding devices for causing the passage of material to be washed through the fluid contained in the pan by passing 90 the same around the drum, a take-off device for removing the material from the drum and causing the same to continue with said feeding devices, said spraying apparatus also serving to deflect the material from the 95 drum, other feeding devices coöoperating with said first-named feeding devices to remove the material therefrom after discharged from the drum and pan and a drying apron operable conjointly with said last-named feeding devices to receive the material and deliver the same in a dry condition.

6. The combination with a supporting frame and a pan supported therein; of a foraminous drum rotatably journaled within the area of the pan, a liquid spraying apparatus mounted in a fixed position within the drum, feeding devices for causing the passage of material to be washed through the fluid contained in the pan by passing the 10 same around the drum, a take-off device for removing the material from the drum and causing the same to continue with said feeding devices, said spraying apparatus also serving to deflect the material from the 10 drum, other feeding devices coöoperating with said first-named feeding devices to remove the material therefrom after discharged from the drum and pan, an apron operable conjointly with said last-named feeding devices to receive the material and deliver the same and means for tightening said apron.

7. The combination with a supporting frame and a pan supported therein; of a

foraminous drum rotatably journaled within the area of the pan, a liquid spraying apparatus mounted in a fixed position within the drum, feeding devices for causing the 5 passage of material to be washed through the fluid contained in the pan by passing the same around the drum, a take-off device for removing the material from the drum and causing the same to continue with said 10 feeding devices, said spraying apparatus also serving to deflect the material from the drum, other feeding devices coöperating with said first-named feeding devices to remove the material therefrom after discharged from the drum and pan, an apron 15 operable conjointly with said last-named feeding devices to receive the material and deliver the same and a collapsible table onto 20 which the material is discharged and collected.

8. The combination with a supporting frame and a pan supported therein; of a foraminous drum rotatably journaled within the area of the pan, a liquid spraying 25 apparatus mounted in a fixed position within the drum, feeding devices for causing the passage of material to be washed through the fluid contained in the pan by passing the same around the drum, a take-off device 30 for removing the material from the drum and causing the same to continue with said feeding devices, said spraying apparatus also serving to deflect the material from the drum and other feeding devices coöperating 35 with said first-named feeding devices to remove the material therefrom after discharged from the drum and pan.

9. A machine for the purpose described, comprising a frame, a semi-circular pan supported in the frame, a screened drum having closed end walls, said drum being rotatably mounted to project into the pan, a supply pipe fixed centrally to the drum and having branches located in close proximity 40 to the periphery of the drum and discharging outward through the same, a drain for the pan, a plurality of rollers rotatably carried by the frame, endless feeding belts engaged around the rollers, certain of said belts passing through the pan and under the drum to convey the paper through the washing fluid, other rollers rotatably journaled in the frame, endless belts engaged around certain of said rollers and an apron engaged around certain of said rollers and coöperating with the belts to remove the paper from the drum.

10. A machine of the class described, comprising a frame, a semi-circular pan supported in the frame, a screened drum having closed end walls, said drum being rotatably mounted to project into the pan, a supply pipe fixed centrally to the drum and having branches located in close proximity 45 to the periphery of the drum and discharging outward through the same, a drain for the pan, a plurality of rollers rotatably carried by the frame, endless feeding belts engaged around the rollers, certain of said belts passing through the pan and under the drum to convey the paper through the washing fluid and means for causing the paper to be removed from the drum at the discharge side of the latter.

11. A machine of the class described, comprising a frame, a semi-circular pan supported in the frame, a screened drum having closed end walls, said drum being rotatably mounted to project into the pan, a supply pipe fixed centrally to the drum and having branches located in close proximity 50 to the periphery of the drum and discharging outward through the same, a drain for the pan, a plurality of rollers rotatably carried by the frame, endless feeding belts engaged around the rollers, certain of said belts passing through the pan and under the drum to convey the paper through the washing fluid and means for causing the paper to be removed from the drum at the discharge side of the latter.

12. A machine of the class described, comprising a frame, a semi-circular pan supported in the frame, a screened drum having closed end walls, said drum being rotatably mounted to project into the pan, a supply pipe fixed centrally to the drum and having branches located in close proximity 55 to the periphery of the drum and discharging outward through the same, a drain for the pan, a plurality of rollers rotatably carried by the frame, endless feeding belts engaged around the rollers, certain of said belts passing through the pan and under the drum to convey the paper through the washing fluid and means for causing the paper to be removed from the drum at the discharge side of the latter.

the pan, a plurality of rollers rotatably carried by the frame, endless feeding belts engaged around the rollers, certain of said belts passing through the pan and under the drum to convey the paper through the washing fluid and means for causing the paper to be removed from the drum at the discharge 65 side of the latter, certain of the belts at the receiving end of the machine being disposed in converged relation toward the receiving point.

11. A machine for treating sensitized paper, comprising a frame, a semi-circular pan supported in the frame, a screened drum having closed end walls, said drum being rotatably mounted to project into the pan, a supply pipe fixed centrally to the drum and having branches located in close proximity to the periphery of the drum and discharging outward through the same, a drain for the pan, a plurality of rollers rotatably carried by the frame, endless feeding belts engaged around the rollers, certain of said belts passing through the pan and under the drum to convey the paper through the washing fluid, other rollers rotatably journaled in the frame, endless belts engaged around certain of said rollers and an apron engaged around certain of said rollers and coöperating with the belts to remove the paper from the drum.

12. A machine for washing sensitized paper, comprising a frame, a semi-circular pan supported in the frame, a screened drum having closed end walls, said drum being rotatably mounted to project into the pan, a supply pipe fixed centrally to the drum and having branches located in close proximity to the periphery of the drum and discharging outward through the same, a drain for the pan, a plurality of rollers rotatably carried by the frame, endless feeding belts engaged around the rollers, certain of said belts passing through the pan and under the drum to convey the paper through the washing fluid, other rollers rotatably journaled in the frame, endless belts engaged around certain of said rollers and an apron engaged around certain of said rollers and coöperating with the belts to remove the paper from the drum, said apron and the second-named belts diverging with respect to each other toward the discharge end of the machine and means carried by the frame to support the paper discharged from the machine.

In testimony whereof I have signed my name to this specification in the presence of two subscribing witnesses.
